CLAIM

The ornamental design for an electronics housing for an automotive controller device, as shown and described.

DESCRIPTION

FIG. 1 is a front view of an electronics housing for an automotive controller device;

FIG. 2 is a rear view thereof;

FIG. 3 is a top view thereof;

FIG. 4 is a bottom view thereof;

FIG. 5 is a side view thereof; and,

FIG. 6 is a perspective view thereof.

The broken lines shown are included for the purpose of illustrating portions of the electronics housing for an automotive controller device that form no part of the claim.
